UNITED STATES PATENT OFFICE

ALVIN G. ARNDT, OF OWOSSO, MICHIGAN, ASSIGNOR TO INDEPENDENT STOVE COMPANY, OF OWOSSO, MICHIGAN, A CORPORATION OF MICHIGAN

DISAPPEARING COOKING TOP FOR TABLE STOVES

Application filed February 26, 1931. Serial No. 518,542.

This invention is a novel improvement in disappearing cooking tops for table stoves, said stoves having portions of their top surfaces provided with fixed permanent covers, 5 also other portions provided with hinged covers below which are mounted the cooking tops of the stoves which carry the gas or other burners, the hinged covers normally concealing the cooking tops when the hinged covers 10 are lowered.

The principal object of the invention is to provide means whereby when the hinged cover of a table stove is swung upwardly to permit use of the cooking top the latter will 15 be automatically raised flush with the permanent cover so that cooking utensils may be slidably moved over from the permanent cover to the cooking top without having to raise or lower such utensils; and whereby when 20 the hinged top is swung down to conceal the cooking top said means will automatically lower the cooking top sufficiently below the hinged cover so that the latter will lie flush with the permanent cover.

Other minor objects of the invention will 25 be hereinafter set forth.

I will explain the invention with reference to the accompanying drawings which illustrate one practical embodiment thereof to enable others to adopt and use the same; and will summarize in the claims the novel features of construction, and novel combinations of parts, for which protection is desired.

In said drawings:

Fig. 1 is a perspective view of a table stove embodying my invention and showing the hinged cover for the cooking top swung upwardly into "open" position.

Fig. 2 is a vertical section on the line 2—2, 30 Fig. 1.

Fig. 3 is a vertical section similar to Fig. 2 but showing the hinged cover in closed position.

Fig. 4 is a horizontal section on the line 45 4—4, Fig. 3.

Fig. 5 is an enlarged section on the line 5—5, Fig. 2.

My invention is illustrated in the drawings in connection with a table stove of the gas- 50 range type, having substantially half of its

upper surface provided with a permanent fixed cover 2, and the other half provided with a swingable cover 3 hinged to the rear of the stove and adapted to be swung from lowered or horizontal position, flush with the fixed cover 2, into substantially vertical position shown in Figs. 1 and 2. The cooking top 4, which preferably comprises an iron casting of slightly less area than the hinged cover 3, is disposed immediately under and 60 in the path of swing of the hinged cover 3, and the cooking top 4 is supported at each side upon wedge shaped blocks 5a carried by elevating bars 5, slidably mounted upon inwardly extending flanges 1a on the side frames 1, 65 said elevating bars 5 being horizontally shifted through suitable linkage by and with the opening and closing of the hinged cover 3. Preferably the gas burners 4a are supported in any suitable manner below openings 4b in 70 the cooking top 4.

Bars 5 carry adjacent their forward and rear ends inclined wedging surfaces 5a adapted to co-act with complementary inclined surfaces 4c on the undersides of the 75 cooking top 4 whereby as the elevating bars 5 are slid on their supporting flanges 1a the cooking top 4 will be correspondingly raised or lowered, the inclination of the inclined surfaces 5a and 4c being such that when the 80 bars 5 are fully retracted towards the back of the stove, i. e. when the hinged cover 3 is in lowered position, the upper surface of the cooking top 4 will lie below the undersurface of the hinged cover 3; and when the sliding 85 bars 5 are moved outwardly towards the front of the stove, i. e. when hinged cover 3 is fully raised, the upper surface of the cooking top 4 will lie flush with the upper surface of the fixed cover 2 of the stove. 90

Suitable flexible connections 6 are provided between the gas manifold 7 (Fig. 4) and the burner inlets whereby the raising and lowering of the cooking top 4 will not affect the feeding of gas from the manifold to the 95 burners.

The hinged cover 3 is hingedly mounted as at 3a to the back frame of the stove and carries adjacent its rear edge a back guard plate 3b extending normal to the cover 3 and adapt- 100

ed, when the cover is swung down into closed position, to form a continuation of the back guard 8 carried by the permanent top 2.

Extending from the rear corners of hinged cover 3 are arms 9 the outer ends of which are respectively connected by links 10 to the rear ends of the slidable elevating bars 5, whereby as the cover is raised and lowered the elevating bars will be pushed forwardly or rearwardly, as the case may be, on their supporting flanges 1a.

The operation is as follows: When the stove is not in use the hinged cover 3 should be lowered as in Fig. 3. The elevating bars 5 will then be shifted to the extreme rear limits of their travel and the cooking top 4 will be automatically lowered into position shown in Fig. 3 so as to be completely covered by the hinged cover 3. When it is desired to use the stove the hinged cover 3 is swung upwardly as shown in Figs. 1 and 2 and in so doing the elevating bars 5 will be moved to their extreme forward limits through the action of arms 9 and links 10, and the cooking top 4 will then be automatically raised, as in Fig. 2, flush with the permanent cover 2, whereby when the stove is in use the surface of the cooking top 4 will be level with the permanent cover 2 so that cooking utensils may be slid from one to the other without raising or lowering such utensils.

I do not limit my invention to the exact form shown in the drawings, for obviously changes may be made therein within the scope of the claims.

I claim:

1. In a stove, a cooking top carrying the heating elements; a pivoted cover for concealing the cooking top when the cover is closed; and cam means automatically operated by the cover for raising the cooking top into the plane of the top of the stove when the cover is opened; said means automatically lowering the cooking top when the cover is lowered.

45 2. In a stove, a cooking top carrying the heating elements; a pivoted cover for concealing the cooking top when the cover is closed; slide bars supporting the cooking top and means operated by the cover for automatically shifting the bars to raise the cooking top flush with the top of the stove when the cover is opened, said means automatically lowering the cooking top below the cover when the cover is closed.

55 3. In a stove having a portion of its upper surface provided with a fixed cover; a cooking top for the other portion, said cooking top carrying the heating elements; a hinged cover adapted to be flush with the fixed cover and for concealing the cooking top when the hinged cover is closed; slide bars supporting the cooking top and means connecting the hinged cover and bars whereby when the hinged cover is raised the cooking top will be automatically elevated flush with the fixed

cover, and when the hinged cover is lowered the cooking top will be automatically depressed below the hinged cover.

4. In a stove having a fixed cover over a portion of its upper surface; a hinged cover over the remaining portion; a cooking top carrying the heating elements normally concealed by the hinged cover when closed; and cam means automatically operated by the hinged cover whereby when the latter is raised the cooking top will be elevated flush with the fixed cover, and when the hinged cover is lowered the cooking top will be lowered below the hinged cover.

15 5. In a stove having a fixed cover over a portion of its upper surface, a hinged cover over the remaining portion; a cooking top carrying the heating elements disposed under the hinged cover; cam bars slidably mounted in the stove for supporting the cooking top; and means automatically operated by the hinged cover whereby when the latter is raised the bars will be shifted to elevate the cooking top flush with the fixed cover, and when the hinged cover is lowered the cooking top will be lowered below the hinged cover.

20 6. In a stove having a fixed cover over a portion of its upper surface; a hinged cover over the remaining portion; a cooking top carrying the heating elements disposed under the hinged cover; bars slidably mounted in the stove carrying inclined surfaces supporting the cooking top; arms on the hinged cover; and links connected with the bars and operated by the hinged cover whereby when the latter is raised the bars will be shifted to elevate the cooking top flush with the fixed cover, and when the hinged cover is lowered the bars will be shifted to lower the cooking top below the hinged cover.

25 7. In a stove having a fixed cover over a portion of its upper surface; a hinged cover over the remaining portion; a cooking top carrying the heating elements disposed under the hinged cover; bars slidably mounted in the stove and having inclined surfaces supporting said cooking top; arms on the hinged cover; and links connecting the arms with the bars whereby when the hinged cover is raised the bars will be automatically shifted to elevate the cooking top flush with the fixed cover, and when the hinged cover is lowered the bars will be shifted to lower the cooking top below the hinged cover.

30 8. In a stove having a fixed cover over a portion of its upper surface; a hinged cover over the remaining portion; a cooking top carrying the heating elements disposed under the hinged cover; bars slidably mounted in the stove and having inclined surfaces; said cooking top having complementary inclined surfaces seating upon those of the bars; arms on the hinged cover; and links connecting the arms with the bars whereby when the hinged cover is raised the bars will be shifted

to elevate the cooking top flush with the fixed cover, and when the hinged cover is lowered the bars will be shifted to lower the cooking top below the hinged cover.

- 5 9. In a stove a disappearing cooking top carrying the heating elements and occupying a portion of the upper surface of the stove; a hinged cover normally lying in the plane of the upper surface and concealing the cooking top
- 10 when the hinged cover is closed; bars slidably mounted in the stove having inclined surfaces engaging complementary inclined surfaces on the cooking top; arms on the hinged cover; and links connecting the arms with the bars
- 15 whereby when the hinged cover is raised the bars will be shifted to elevate the cooking top into the plane of the upper surface of the stove, and when the hinged cover is lowered the bars will be shifted to lower the
- 20 cooking top below the hinged cover.
